UNITED STATES PATENT OFFICE.

HARRY B. REDDING, OF COLUMBUS, OHIO, ASSIGNOR, BY DIRECT AND MESNE ASSIGNMENTS, OF TWO-THIRDS TO I. S. FINK, OF COLUMBUS, OHIO, AND ONE-THIRD TO THE REDDING VALVE COMPANY, OF COLUMBUS, OHIO, A CORPORATION OF DELAWARE.

VALVE.

Application filed January 16, 1920. Serial No. 351,803.

To all whom it may concern:

Be it known that HARRY B. REDDING, a citizen of the United States, residing at Columbus, in the county of Franklin and 5 State of Ohio, has invented certain new and useful Improvements in Valves, of which the following is a specification.

This invention relates generally to valves, and has particular reference to the valve body or fluid controlling closure thereof, the 10 general object of the invention being to provide a valve in which is mounted a sliding closure of novel construction and of such form as to positively effect the closing of the 15 fluid conduit of the valve when said closure occupies a lowered position.

Another object of the invention resides in a valve body or closure which consists in the provision of a retaining cage in which are 20 slidably mounted valve closing side members, the latter having oppositely situated reversely inclined plane faces, to produce opposed wedges between said members which are adapted to be positioned within 25 tapering sockets formed by the presence of said inclined faces, in connecting an actuating stem with one of said wedges in such manner that the closure as a whole will be supported in depending relation from said 30 stem, and in the provision of a projection upon the other of said wedges, said projection serving when engaged with a fixed portion of a valve casing to arrest movement on the part of the closure and, in conjunction 35 with said stem, to force said wedges inwardly of said tapering sockets, in order that said wedges may act upon the inclined faces of said side members so as to forcibly spread the latter into fluid sealing engagement 40 with a plurality of valve seats.

A further object of the invention resides in mounting anti-friction devices between said wedges and the inclined faces of said side members, in order that there will be an 45 absence of undue friction between parts and to prevent excessive wear.

Other objects of the invention reside in the provision of a valve which is of very economical construction, fully capable of 50 withstanding high internal pressures and various thermal conditions, and one which will be convenient in which to make repairs, positive in action and easy to properly actuate.

For a further understanding of the invention, reference is to be had to the following description, and to the accompanying drawings, in which:

Figure 1 is a vertical longitudinal section taken through the valve comprising the 60 present invention, and showing the closure body in its lowered or conduit sealing position.

Figure 2 is a similar view disclosing the closure in its elevated or inactive position.

Figure 3 is a detailed sectional view taken along the plane disclosed by the line 3—3 of Figure 1, the stem and wedges being shown in elevation.

Figure 4 is a horizontal sectional view 70 taken along the line 4—4 of Figure 1.

Figure 5 is a detailed perspective view of the retaining cage.

Figure 6 is a side elevation of one of the 75 side members of the closure body.

Figure 7 is a vertical sectional view through said side member.

Figure 8 is a detailed perspective view of 80 the lower wedge employed in the closure, and.

Figure 9 is a similar view of the upper 85 stem carried wedge.

Referring more particularly to the details of the invention, use is made of a valve 1. In its preferred form this valve consists of a lower casing 2 in which is formed a closure chamber 3 and an intersecting fluid conduit 4. The exact formation of the casing 2 does not in itself form a part of the present invention, but is the subject matter of my 90 Patent Number 1,370,224, issued March 1, 1921, and 1,370,225, issued March 1, 1921.

The outer ends of the conduit 4 may be provided with fixed rings 5, by means of which communicating pipes, not shown, may be connected with the valve. Slidably mounted within the chamber 3 is a closure or valve body 6, which is adapted to be moved into and out of registration with the conduit 4 for the purpose of governing 100 the flow of fluid therethrough. As shown in Figure 2, when the closure is elevated the conduit will be left open to permit of the unrestricted passage of fluid therethrough, and, conversely, when the closure 105 is lowered to assume the position shown in Figure 1, said conduit will be effectively obstructed and the passage of fluid through

the valve correspondingly prevented. The chamber 3 is of such proportions as to receive the closure when the latter is in its elevated or inactive position, so that the closing of the conduit 4 may be regulated by the slideable operation of the valve body 6.

To raise and lower the closure, use is made of a vertically extending threaded stem 7 which has its lower end secured to the closure 5 and its upper threaded end provided with an engaging hand wheel 8, whereby upon the rotation of the latter said stem and the closure body may be raised or lowered. The upper portion of the casing 2 terminates in an out-turned flange 9, upon which is positioned the base plate 10 of the valve superstructure. This plate may be bolted or otherwise secured as at 11 to the flange 9 for the purpose of providing a substantial base for the stem supporting structure. The base plate 10 is further provided with a central opening through which the stem 7 slidably projects, and this opening is suitably packed by means of a stuffing box construction 12, which operates to prevent the seepage of fluid through the opening in the base plate. If desired, the stuffing box may consist of a cup 13, formed with the base plate 10 and adapted to contain a suitable packing material 14 which is so placed as to surround and engage with the stem 7. In the upper end of the cup there is telescopically inserted a slideable member 15, the lower end of which being adapted to engage with the material 14 for the purpose of crowding the latter into fluid sealing engagement with the stem 7. The adjustment of the member 15 is provided for by means of threaded bolts 16 which rigidly arise from the plate 10. The upper ends of these bolts are equipped with nuts 17, which may exercise sufficient force upon the member 15 to force the latter into operative engagement with the material 14.

To support the operating wheel 8 and to protect the stem 7, use is made of a strut member 18. The construction of this member has been particularly set forth in my aforesaid patents, but for present purposes it may be said that the same comprises a pair of downwardly and outwardly converging legs 19, the lower ends of which being suitably connected in any rigid manner with the base plate 10. The upper portions of said legs terminate in a sleeve 20, in which is rotatably positioned the fixed hub 21 of the hand wheel. This hub is provided with an annular groove for the reception of the sleeve 20, in order that the rotation of the wheel will not result in its vertical change of position, or in other words to insure a vertical movement on the part of the stem 7 only.

Referring now to the more important part of the present invention, it will be observed that the lower end of the stem 7 is provided

with a transverse opening through which a pin 22 is arranged to project. This pin connects said stem with an upper wedge element 23, the latter being formed with a collar 24 designed for the reception of the lower end of said stem, and it is through this collar that the pin 22 projects. The body portion of the wedge 23 is considerably wider than the collar 24 to provide shoulders 25 upon which are positioned a retaining ring or cage structure 26. In this instance the structure 26 is of annular formation, and is provided with upper and lower openings 27 and 28 respectively, the former being designed to receive the collar 24, while the latter is arranged to receive a depending stud or projection 29 formed upon a lower wedge element 30, the latter being situated in opposition to the wedge element 23. It will thus be manifest that through the provision of the shoulders 25, the wedge element 23 or the stem 7 will serve to support the ring or cage structure 26 and the mechanism carried thereby.

Slidably positioned for lateral movement within the structure 26 is a pair of side or conduit closing members 31. In this instance these members have been exemplified as of disk shaped formation and, as shown in Figures 6 and 7, the same are provided on one side with recesses 32, the side walls 33 of which being formed to present reversely inclined plane surfaces. When the members 31 are operatively situated, the recesses 32 thereof will be arranged in opposition to each other so as to provide substantially tapering sockets 34 between their side walls, and it is within these sockets that the upper and lower wedges are designed to be positioned. Annular wear rings 35 are provided upon the outer circumferential portions of the side members 31, and are adapted when the closure is lowered to be pressed into engagement with valve seats 35' removably positioned in the inner ends of the conduit 4. These seats are provided with radial lugs 36 by means of which a suitable tool may be connected with the seats for the purpose of removing the latter. Opposite sides of the chamber 3 are provided with vertically extending guide ribs 37, these ribs are arranged to be positioned between bifurcated lugs 38 which project from the sides of the ring structure 26, said ribs and lugs serve to guide the cage structure in its operative movements.

It will thus be manifest that when it is desired to close the valve, the hand wheel 8 will be operated so as to cause a lowering of the stem 7. This operation continues until the projection 29 contacts with the bottom of the chamber 3, thus arresting movement on the part of the closure or valve body so as to position the latter in registration with the conduits 4. Continued rotation on the

part of the hand wheel will then result in forcing the upper wedge 23 downwardly into its socket 34 with sufficient pressure to forcibly spread the side members 31 so as 5 to cause the latter to frictionally engage with the valve seats 35'. Not only does the upper wedge element accomplish this function of spreading the side members but the lower wedge member 30 is also used in the same 10 capacity and with similar efficiency. It is obvious that the stud 29 can not move farther downwardly in the chamber 3 when the parts are in the position recited so that downward movement on the part of the 15 wedge 23 will result in upward movement of the lower wedge, which crowds into its socket 34 so as to expand the lower portions of the side members in unison with the upper portions thereof. Thus, the side members 20 may be operated upon so as to produce a firm circumferential seal around the full circumference of the valve seats. Upon the elevation of the closure structure, the upper wedge element will be partially withdrawn 25 from its wedged engagement with the side members. This results in permitting said wedge members to move inwardly so that they will not exercise undue friction on the valve seats during the initiation of upward 30 movement of the closure. Since the pressure on the upper portions of the members 31 has been removed, it follows that upon the raising of the valve body the lower wedge element will simply gravitate to its 35 lowered position, thus allowing the members 31 to freely contract. If desired, I provide rollers or other similar anti-friction devices 39 between the wedge elements 23 and 30 and the inclined faces 33 of the side 40 members 31. By the presence of these anti-friction elements, the operation of the wedges will be rendered more positive and effective, by reason of the fact that the pressures which said wedge elements will exercise will 45 be directly imparted to the side members and will not be lost in undue friction. Also, the elements 39 permit of the convenient release of the wedge elements from expanding engagement with the side members upon 50 the upward movement of the stem.

From the foregoing description taken in connection with the accompanying drawing, it will be apparent that there is provided

a valve wherein a closure structure of novel and efficient formation is to be found. This 55 construction is designed to be an improvement upon the ordinary form of a wedge shaped valve, and to eliminate the tapering seats hitherto provided for such valves. By the provision of the opposed wedge elements 60 a positive expansion of the side members 31 is to be had, and the pressures are so applied as to insure close engagement between the side members and the valve seats around the 65 entire circular bearing portions of the side members. The pressures which the wedge elements may supply to the side members are very effective, so that a seepage of fluid though the closure structure is rendered substantially impossible. By use of the laterally expanding side members, tapering valve seats are dispensed with and likewise are the defects which are incidental to their use. 70

I claim:

In a valve, a casing including a longitudinally extending fluid conduit and an intersecting closure chamber, a slidable closure arranged for movement within said chamber to control fluid passage through said conduit, said closure comprising an actuating stem movable longitudinally of said chamber, a wedge element carried by the inner end of said stem, a circular cage member supported upon said wedge element, a second wedge element positioned in said cage and located in registration with but in opposed relationship to said first wedge element, a projection extending from said second wedge element and arranged to pass through an opening provided in said cage member, a pair of closure disks mounted in said cage member and including reversely inclined surfaces arranged for cooperation with the similar surfaces of said wedge elements, whereby when said wedge elements are moved toward each other said disks will be forced apart into seating engagement with valve seats provided in conjunction with said conduit, longitudinally extending stationary ribs carried by the walls of said closure chamber, and guide lugs projecting from said cage member and adapted for cooperation with said ribs. 75 80 85 90 95 100 105

In testimony whereof I affix my signature. 105
HARRY B. REDDING.
